UNITED STATES PATENT OFFICE.

FRED W. H. KELLER, OF WESTERN, NEBRASKA.

BRACKET FOR HAY-FORK TRACKS.

SPECIFICATION forming part of Letters Patent No. 794,942, dated July 18, 1905.

Application filed April 14, 1905. Serial No. 255,618.

To all whom it may concern:

Be it known that I, FRED W. H. KELLER, a citizen of the United States, residing at Western, in the county of Saline and State of 5 Nebraska, have invented certain new and useful Improvements in Brackets for Hay-Fork Tracks, of which the following is a specification.

This invention relates to improvements in 10 tracks for hay-carriers; and it consists, essentially, of a device whereby the track may be extended a short distance outside of the barn. This has the advantage that the hay does not 15 come into contact with the barn, and therefore enables the hay-fork to be easily operated.

Reference is to be had to the accompanying drawings, in which—

Figure 1 is a perspective view showing the 20 device applied. Fig. 2 is a perspective view showing it detached. Fig. 3 is a front elevation.

Corresponding and like parts are referred 25 to in the following description and indicated in all the views of the drawings by the same reference characters.

The numeral 1 indicates a metal bar which projects outward from the gable of a barn, one end 2 of which is reduced in size and 30 threaded for the reception of a nut 3. The reduced end 2 of this bar is passed through openings in the roof-rafters, so that the shoulder 4 is brought against the front of the barn. The nut 3 is then screwed up against the 35 adjacent rafter, so that the bar 1 is held securely against longitudinal movement.

It will be perfectly obvious that the reduced portion may be made of any suitable length to pass through any required number

of rafters. Braces 5 and 6 are employed to 40 support the end of the bar 1 to prevent it from sagging. These braces are bolted at one end to the end of the projecting bar 1 and are provided at the other end with cross-pieces 7, which fit against and are fastened to 45 the side of the barn. Hangers 8 are suspended from the bar 1 and the track 9 attached thereto. As shown in the drawings, one of the hangers 8 is attached to the end of the bar 1 and another attached at an intermediate point. The hangers are preferably 50 formed with a yoke 10 at one end, the arms of which embrace and are fastened to the bar 1.

From the foregoing description it will be 55 readily understood that I have devised an improvement in tracks for hay-carriers which is very simple in construction and which will at the same time be very durable in use.

Having thus described my invention, what 60 I claim as new is—

The combination with the usual track of a bracket for supporting an extension thereof, said bracket comprising a bar having a reduced and threaded end adapted to pass 65 through a number of rafters, braces attached to the projecting end of said bar and provided at their opposite ends with cross-bars to fasten to the side of the barn, and hangers suspended from the projecting bar and having the track attached thereto.

In testimony whereof I affix my signature in presence of two witnesses.

FRED W. H. KELLER. [L. S.]
